UNITED STATES PATENT OFFICE.

WILLIAM S. HAMM, OF BOSTON, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

1,106,377.

Specification of Letters Patent. Patented Aug. 11, 1914.

Application filed June 30, 1905, Serial No. 267,700. Renewed October 28, 1912. Serial No. 728,268.

To all whom it may concern:

Be it known that I, WILLIAM S. HAMM, of Boston, in the county of Suffolk and State of Massachusetts, have invented certain new and useful Improvements in Lasting-Machines, of which the following is a specification.

This invention relates to lasting machines and has for its object to improve machines of this class and also to provide certain special features by which the machine is adapted for use in lasting expeditiously high grade stitchdown shoes.

Important features of the invention are to be recognized in novel combinations of shoe holding means with certain lasting instrumentalities; in the lasting instrumentalities themselves; and in the mounting and operating mechanisms therefor. Among the novel features especially adapting the machine for making stitchdown shoes may be mentioned the provision of the continuous support fitting the last around the toe and along the sides over which to lay out the margin of the upper; the formation in this supporting means of a welt or other retainer receiving seat to facilitate the application of such a retainer to the shoe; and the use in a stitchdown lasting machine of a support having a non-rigid face over which the flange is out turned and may be pressed, beaten or otherwise shaped to establish it in its acquired form without liability of weakening the stock along the line over which it is outturned. These and other features of the invention, including certain combinations of parts and more important details of construction will now be described in connection with the accompanying drawings which represent a preferred embodiment of the invention and in which,—

Figure 1 shows in side elevation a machine designed to last shoes according to my improved system. Fig. 2 is a top plan view thereof. Fig. 3 is a rear end elevation. Fig. 4 is a longitudinal section similar to Fig. 1. Fig. 5 is a sectional detail of one of the wiper supports. Fig. 6 is a section on the line 6—6 of Fig. 5. Fig. 7 is a section on the line 7—7 of Fig. 4. Figs. 8, 9, and 10 show in cross-section a last and shoe together with the side-formers, in successive steps of the lasting operation. Fig. 11 shows the same shoe after it has been sewed. Fig. 12 is a longitudinal section of a last and up-

per showing how the forepart and the heel of the upper are folded outwardly and inwardly respectively. Fig. 13 is a modified form of a former with means for adjustment.

Referring to the drawings, on which the same reference characters indicate the same parts in all the figures:—A base 10 is shown as supporting a table 11 which is pivoted thereon by a stem 12, and which is adapted to be swung about the axis of said stem to any convenient position. A sliding carriage 111 is arranged to slide in guides 112 formed on the table 11 and is adapted to carry an upright-post or jack 13. The lower end of the jack 13 is screw-threaded as at 14, and is adapted to be screwed into an internally threaded bevel-gear 15, rotatably secured in the under side of the carriage 111. A beveled gear 16, intermeshing with the gear 15, is affixed to one end of a stem 17 suitably journaled in a boss formed on the carriage 111. The outer end of the stem 17 is provided with a hand-wheel 18 by which the gears may be rotated to raise or lower the screw-threaded jack 13 in the gear 15, for the purpose of adjusting the height of the shoe to that of the formers hereinafter described. The upper part of the jack is bifurcated and at the end thereof a stud 19, adapted to enter the aperture in the top of a last 20, is pivoted at 21 between the sides of the jack. The under edge of the stud 19 is formed as a toothed segment 22 which intermeshes with a segment 23 formed on the upper end of a lever 24 pivoted at 25 also between the sides of the jack. The lower end of the lever 24 projects rearwardly and has a ball-and-socket connection 26 with a stem 27. Said stem is screw-threaded in a block 28 which is hung on trunnions 29 connected to ears 30 projecting from the carriage 111. The rear end of the stem 27 is provided with a handwheel 31 whereby the stem may be screwed through the block 28 and so rock the lever 24 and consequently the stud on which the last is mounted. A portion of the lever 24 occupies a slot 113 formed in the carriage 111 and so acts as a spline to keep the jack from turning. A toe-rest 32 for the last 20 is supported upon a sliding carriage 33 which, like the carriage 111, is arranged in the guides 112. The lower portion 35 of said toe-rest is formed as a stem, and occupies a hole 110

formed in the carriage 33 to receive it. A lower portion 35 of the toe-rest is threaded to receive a threaded collar 36, which rests upon the top of the carriage 33 and is adapted to adjust the height of the toe-rest relatively thereto. A screw-plug 37 in the carriage 33 enters a slot 38 cut longitudinally in the threaded portion 35 and so prevents the toe-rest from turning.

10 When an upper has been placed upon a last and the last upon the pin 19, the last is adapted to be rocked forward by a rotation of the hand-wheel 31 until the toe is brought to bear upon the rest 32, and firmly held thereby. The carriage 33 carries in addition to the toe-rest, a flexible toe-clamp or former 39, over which the vamp is adapted to be folded outwardly. The clamp or former 39 is mounted upon a sliding support 40 held in guides 41 on the carriage 33. It extends around the toe and a short distance along each side thereof. The ends of the former are hung on links 42 42 which are pivoted to compressing arms 43 43 pivoted together at 44 upon a rocker 45. The rocker 45 is pivoted by a stud 46 in the upper end of the support 40, and its under edge is formed as a toothed segment 47 which intermeshes with a hand-operated worm 48 also mounted in the support 40. By means of the worm 48, the former 39 may be rocked and so be set to conform to the inclination of the sole face of the last. The upper edge of the former is adapted to lie nearly flush with the sole face of the last and to be firmly pressed against the upper by forcing together the arms 43 43. For this purpose a rod 49, (see Fig. 2,) screw-threaded at one end and having at its other end a hand-wheel 50 is passed through a swiveled block 51 at the free end of one of the arms 43 and screwed into a swiveled block 52 carried by the free end of the other arm. Rotation of the rod 49 causes the arms 43 43 to be drawn together with the result already referred to.

As previously stated, the carriages 111 and 33 are adapted to slide in the guides 112 on the table 11, and to move them in said guides a rod 53 is mounted lengthwise between the 50 guides and has portions 54 and 55 which are screw-threaded into said carriages by threads of opposite pitch. A sleeve 56, arranged upon the rod 53, between a shoulder 57 and a hand-wheel 58 thereon, is screw-threaded 55 into a boss 114 secured upon the table 11 at the forward extremity of the guides 112. The sleeve 56 permits of a rotation of the rod 53 but does not permit any axial movement thereof. A rotation of the rod 53 by 60 the hand-wheel 58 draws the carriages 33 and 111 toward each other or separates them according to the direction of rotation. By screwing the sleeve 56 back or forth in the boss 114 the rod 53 and the carriages may 65 be moved together in one direction or the

other to vary the longitudinal position of the last and the toe former.

For giving the former 39 an independent horizontal travel, to force it against the toe of the shoe, a forked rod 59, straddling the 70 support 40 is attached thereto by a pin 60, of which each end occupies a slot 66 formed in each leg of the forked portion. The free end of the rod 59 extends through an opening 61 in the carriage 33 and is supported therein by a pin 62. The upper side of the rod 59 is provided with ratchet teeth 63 with which a pawl 64 is adapted to coöperate. The pawl 64 is mounted in the opening 61 above the rod 59 upon a stem 65 which extends through the carriage, and when said pawl is in engagement with the ratchet 63, it prevents the rod 59 from receding. A lever 67, pinned to and between the projecting ends of the fork by a pin 68, has a cam-face 69 adapted to bear upon the perpendicular face of the support 40. When the carriages 33 and 111 are drawn together the support 40 is adapted to be slid toward the shoe and being held thereby the pawl 64, it may be given an additional movement to cause the former 39 to bind the shoe more firmly by lifting the handle 67 from the position shown by dotted lines in Fig. 1 to the position indicated by full lines. The additional movement given to the support 40 by the lever 67 is permitted by the pin-and-slot connection 60 66 of the fork 59 with said support. The outer end of the stem 65 carries a handle 70 which is normally held 100 downward by a spring 71. The pawl 64 being fast on the stem 65, is of course held against the ratchet 63 by the spring 71, but when it is desired to free the former 39 from the shoe, it is done by lifting the handle 70 105 and allowing the support 40 to recede.

It has been shown how the shoe is adapted to be mounted and positioned and how the toe-former is positioned and manipulated. The mechanism hereinafter described is instrumental in forming the sides of the shoe and in positioning the welt.

As a result of folding the vamp outwardly, as previously stated, the shoe is formed with what is termed an "extension sole." The 115 majority of shoes having "extension soles" are provided with heel-lifts which do not extend outside of the contour of the upper at the heel. In other words, they have an extension sole and a flush heel, and in order 120 to make a shoe by this improved system, to conform to the predominant style, the extension or outturned edge of the vamp is carried as far back as the breast of the heel. The welt-strip, therefore, extends back on 125 each side the same distance as the out-turned edge of the upper and at this point the upper is incised and the heel portion turned in and lasted in the usual way. On the other hand, in lasting a shoe having an extension heel, 130

as well as extension sole, as the case may sometimes be, the entire edge of the upper may be folded outwardly and a continuous welt-strip extending entirely around the sole 5 may accomplish the result just specified. However, on the accompanying drawings, the machine illustrated is designed to produce an extension-sole and a flush heel. To that end, in addition to the flexible toe-former, there are provided rigid, interchangeable side formers which engage the shoe as far back as the heel. It may be seen, however, that a flexible heel-former, similar to the toe-former might be incorporated to 10 produce a shoe having an extension heel, as well as an extension sole.

Referring more particularly to Fig. 2, it will be seen that there are two formers 72 72 which flank the ball of the shoe and two 20 more, indicated at 73 73, which flank the shank of the shoe. The formers 72 72 and 73 73 are independently mounted but when in operative position, as shown in Fig. 2, they, together with the toe-former, present 25 to the forepart of the shoe, a continuous surface over which the vamp is adapted to be folded. The edges of the side formers are recessed as at 74 so that the recessed surfaces lie flush or on a plane with the top of 30 the toe former 39. Prior to the folding of the vamp, a welt strip is laid along the upper edge of the former 39 and in the recesses 74 and left, during the lasting of the shoe, which is hereinafter fully described.

35 The formers 72 and 73 are similarly mounted upon upright posts or stems 75, to which they are connected by screws as shown in the drawings to permit of the slight adjustments about axes extending transversely of 40 the last which are desirable for adapting the formers to different styles of lasts; these stems being secured in apertures 76, formed in rock-arms 77. Said formers approximate the contour of the sides of the shoe to be 45 formed, and are arranged to engage the upper on the last at substantially the sole line, that is, the line forming the junction of the sides and the sole face of the last. The rock-arms 77 are loosely mounted upon rods 78 50 extending longitudinally of the table 11, and secured in brackets 115 projecting therefrom. Bushings 80 and 81 are arranged in an aperture 79 extending across and slightly intersecting the aperture 76 in each rock-arm, so that said bushings may be made to 55 partly occupy the aperture 76. The bushings are cut away at this point so as not to obstruct the aperture 76, thus allowing a free passage for the reception of the stem 60 75. A bolt 82, extending through the bushing 80, and screw-threaded into the bushing 81, is adapted, when screwed up, to force said bushings together so that the edges adjacent to the aperture 76 bite upon the stem 65 75, and firmly bind it in the arm 77. The

bushings 80 and 81 are locked in the arm 77 by the presence of the stem 75, and the stem 75 in turn is locked in the arm 77 by the bushings when they are compressed. The lower end of the arm 77 is bifurcated, as 70 indicated at 83, and in the space thus formed a lever 84 is pivoted on the rod 78 between the two sides of the arm 77. That portion of the lever 84 which sets into the arms 77 is provided with a face 85 which is adapted 75 to coact upon a plug 86 occupying a chamber 88 formed in the arm 77. A spring 87 is coiled about the stem of the plug 86 between the head thereof and the inner wall of the chamber 88. When the lever 84 is 83 rocked toward the shoe, it causes the arm 77 to exert a yielding pressure of the former against the shoe by reason of the spring-pressed plug 86. A pin 92, passing through a slot 93 in the lever 84 is fixed in the arm 85 77 and provides a positive backing for said arm, in addition to the yielding one provided by the plug 86. The lever 84 is further provided with ratchet-teeth 89 formed upon an arc of which the rod 78 is the center. Pawls 90, pivoted upon rods 91, extending parallel to the rods 78, are adapted to coöperate with the ratchet-teeth 89, in holding the levers 84 against receding from the position to which they have been set. A collar 94 is pinned to 95 the rod 91 adjacent to each pawl 90, and upon each collar is a lifting-dog 95 which normally lies under a projection 96 formed on each pawl. The rods 91 are adapted to be rocked in bosses 116 formed on the brackets 100 115 and are provided with hand-wheels 97 affixed to their forward ends by means of which the rods may be rocked to lift the pawls out of engagement with the ratchets and so release the formers. The levers 84 105 110 are so mounted that they have a tendency, due to gravity, to recede from the jack, consequently when released, they act as weights to automatically rock the arms 77 away from the shoe by means of the pins 92. Springs 98, connected to fingers 99 affixed to the rear ends of the rods 91, serve to return said rods to their normal position, in which the pawls are disengaged from the 115 lifting-dogs 95.

The four side formers 72 72, 72 and 73 73 are set and left against the shoe during the entire lasting operation, being held by the pawls 90. Sufficient pressure should be given to the levers 84 in setting the formers 120 against the shoe so that said formers may press the upper against the sides of the last and so prevent it from slipping thereon. While the leather is being manipulated, the last is, of course, subjected to slight movements one way or another, but the backing received by the arms 77 from the springs 88 keeps the formers constantly against the upper and prevents the latter from slipping. Since the formers 72 and 73 are in- 125 130

dependently mounted and manually movable, they can be set to impart just the pressure desired for the best results in connection with differently formed lasts. But by 5 actuating the shafts 91, the formers on either side can be released simultaneously.

Referring now to Figs. 8 to 12, it will be seen that the first operation, after assembling an upper *b*, a lining *d*, and an inner 10 sole *c* on a last 20, and positioning the same on the machine, and setting the several formers against it, is to pull the upper *b* tightly about the last. In so doing, the edges *b'* may be drawn between the formers and the 15 last while said formers are exerting pressure thereon. The pressure thus exerted maintains the upper in a taut condition while a cement-coated false welt-strip *a* is laid in the recesses 74 and around the shoe, 20 (see Fig. 8.) The next step is to snip the edge *b'* on each side of the shoe on a line even with the breast of the heel, as indicated at *b*² in Fig. 12. The heel portion, from the 25 incisions *b*² back, is folded inwardly and lasted in the usual manner. The forepart, back as far as the incisions *b*², is then folded outwardly over the cement-coated false 30 welt *a*, (see Fig. 9). The upper constitutes a non-rigid surface over which the margin 35 of the upper is outturned and avoids liability of weakening the welt along the line on which it is turned outwardly and may be pressed or beaten to shape it. The coating of cement between the lining *d* and the insole *c* serves to hold them firmly together without any further means, while the cement between the false welt *a* and the outturned edge *b'* serves a like purpose in addition to rendering the seam water-proof. The outer 40 sole *c* and the edges of it cover the edge *b'* 45 10,) so that the body of it covers the inner sole *c* and the edges of it cover the edge *b'* of the upper *b*. Here again a coating of cement may be administered to the inner 50 surface of the outer sole *c*; so that said outer sole will adhere to the inner sole and to the out-turned portion of the upper *b*. The shoe thus far lasted has been shaped and assembled and the component parts cemented 55 together so that the last and the shoe may be removed from the machine without disturbing the parts assembled.

In removing the shoe from the machine, the welt-strip *a* being cemented to the edge *b'* of the upper *b*, remains with the shoe, and ready to be sewed thereto. The sewing of outer-sole *c* and welt-strip *a* to the edge *b'*, as shown by Fig. 11, does not in any way differ from the usual operation of sewing an outer sole to a welt which has been previously sewed to an upper and inner sole.

It will be seen that the upper, in being sewed, as it is, between the two other parts, is attached to the sole in the firmest manner possible. While the welt-strip takes up the

stitches and prevents them from pulling through or cutting the upper, its inner edge constitutes a positive form for the outline of said upper, and is therefore a means for preserving the original shape of the shoe. 70 It will also be observed that the vertical walls of the recesses 74 in which the welt is seated constitute molds by which the welt is shaped edgewise and accurately positioned to conform to the contour of the side of the 75 shoe.

Referring now more particularly to the operation of the machine, let it be supposed that an upper *b* and lining *d* have been placed upon a last 20 and the latter mounted upon the jack as already described. The toe-former 39 is adjusted by means of the worm 48, the lever 67 and the hand-wheel 50 to fit snugly around the toe so that the loose edge *b'* of the vamp *b* extends above it. The side formers 72 72 and 73 73 are then rocked into engagement with the shoe by means of the levers 84 and held there by the pawls 90. The lasting or assembling of the several parts of the shoe is then promoted as herein-before explained.

Upon the completion of the lasting operation, the shoe is ready to be removed from the machine. The side formers are released by a slight rotation of the hand-wheels 97, and the toe-former by depressing the lever 67. The shoe is then freed from the toe-rest 32 by rotating the hand-wheel 31 or 18, or both, and is then free to be removed from the jack. The toe-former being flexible, is, of course, adaptable to any size or style of shoe, but the side formers are made interchangeable so that they may be removed from the stems 75 and others of various styles substituted therefor.

Fig. 13 illustrates a clamp or former having provisions whereby it may be adjusted to receive false welts of various widths. The former 73, instead of having its thicker portion integral with the thin edge 74, shown in Fig. 5, is made in two parts or layers, its lower part being flat and provided with slots 730. A plate 731 whose inner edge is of the same curvature as that of the lower part is adjustably clamped to the upper face of said lower part by screws 732 which extend through the slots 730 and are threaded into the under side of said plate. For lasting a shoe having a wide extension sole and consequently a wide welt, the plate 731 may be moved farther from the inner edge of the lower part and clamped at any position. By using screws which do not project above the surface, the same flat surface for supporting the out-turned upper may be maintained. This structure is practically identical with that shown in Fig. 5, in presenting a former, the inner edge of which is recessed, but enables the width of the recess 741 to be varied for the reception of the welt. 130

Having thus explained the nature of the invention, and described a way of constructing and using the same, although without attempting to set forth all of the forms in which it may be made, or all of the modes of its use, I declare that what I claim is:—

1. A lasting machine comprising a jack for the last, a series of formers presenting a continuous edge to the sole line of the forepart of the shoe, each former having an outwardly extending flat surface as described, and manually operable means for causing each of said formers independently to exert a yielding pressure against the shoe.

2. A lasting machine comprising a jack for the last, a flexible former adapted to extend horizontally around the toe of a shoe along the line of the inner sole, means for adjusting and contracting said former against the shoe, and rigid formers forming continuations of said flexible former and adapted to be brought independently into contact with each side edge of the shoe along the line of the edge of the inner sole, said rigid formers having outwardly extended flat surfaces substantially as set forth.

3. A lasting machine comprising a jack for the last, a flexible former adapted to extend horizontally around the toe of a shoe along the line of the inner sole, means for adjusting and contracting said former against the shoe, rigid formers forming continuations of said flexible former and adapted to be brought into contact with each side edge of the shoe along the line of the edge of the inner sole, each of said rigid formers having an outwardly extended flat surface, and means for causing each rigid former to exert an independent yielding pressure against the shoe.

4. A lasting machine comprising a toe-former adapted to extend around the toe of a shoe so that its upper edge is approximately on the plane of the inner sole, formers adapted to extend along the sides of the shoe and having their inner edges recessed for the reception of a welt-strip and forming continuations of the upper edge of the toe-former, and means for causing said side formers to clamp the upper yieldingly against a last.

5. A lasting machine having a last-support and formers having flat surfaces over which the edge of the upper is adapted to be outwardly folded, said formers comprising a toe-former, rods having arms adapted to rock thereon, and a plurality of formers on each side of the shoe, each former being independently and adjustably mounted on one of said rock-arms.

6. A lasting machine having a last-support and formers having flat surfaces over which the edge of the upper is adapted to be outwardly folded, said formers comprising

ing a toe-former, rods having arms adapted to rock thereon, a plurality of formers on each side of the shoe, each former being independently and adjustably mounted on one of said rock-arms, and means for rocking said arms toward the shoe.

7. A lasting machine comprising a jack for the last, a plurality of rock-arms on each side of the jack and adapted to be rocked toward and from the jack, means for rocking each of said arms independently toward the last, means for locking said arms against receding movement, and means whereby the rock-arms on either side may be simultaneously released.

8. A lasting machine comprising a jack for the last, a plurality of formers on each side of the last, each former being adjustably secured to an independent rock-arm adapted to rock toward and from said last, means for rocking each of said formers independently to contact with said last, independent means for locking said formers in contact with the last, and means for causing the locking means of each plurality of formers to release said formers simultaneously from contact with the last.

9. A lasting machine comprising a jack for the last, a series of formers adapted to be engaged with the edge of a shoe on the plane of the innersole, said formers having flat outwardly extending surfaces over which the upper is adapted to be outwardly folded, means for independently engaging said formers with the shoe, means for automatically locking said formers against a shoe, and means for releasing said formers.

10. A lasting machine comprising a jack for the last, and a series of formers of which the upper faces at their inner edges are recessed, said formers being movable into engagement with the edge of a shoe on the plane of the inner sole, said recessed edges forming a substantially continuous groove for the reception of a welt-strip when the formers are thus engaged with the shoe.

11. A lasting machine comprising a jack for the last, a series of formers of which the upper faces at their inner edges are recessed, said formers being movable into engagement with the edge of a shoe on the plane of the inner sole, said recessed edges forming a continuous groove for the reception of a welt-strip when the formers are thus engaged with the shoe, and means for moving said formers to clamp the upper against the sides of the last.

12. A lasting machine comprising a jack for the last, a series of formers of which the upper faces at their inner edges are recessed, said formers being movable into engagement with the edge of a shoe on the plane of the inner sole, said recessed edges forming a continuous groove for the reception of a welt-strip when the formers are thus en-

gaged with the shoe, said faces constituting supports for the outwardly spread edge of the upper, means for engaging said formers with the shoe, means for locking said formers against the shoe, means for releasing said formers, and means for causing them when released to automatically recede from the shoe.

13. A lasting machine comprising a jack 10 for the last, a series of formers of which the upper faces at their inner edges are recessed, said formers being movable into engagement with the edge of a shoe on the plane of the inner sole, said recessed edges forming a 15 continuous groove for the reception of a welt strip when the formers are thus engaged with the shoe, means for engaging said formers with the shoe, and means for locking said formers against the shoe.

14. A lasting machine comprising a table, a jack for supporting a shoe, a former adapted to engage the toe of the shoe, a movable support for said former, means for inclining said former to conform to the inclination of 25 the innersole, a movable carriage on which said support is movable, means for moving said carriage endwise toward and from the shoe, said means being adapted to hold said carriage wherever it is moved, means carried 30 by said carriage for forcing said support shoeward on said carriage, and means for automatically locking said support against receding.

15. A lasting machine comprising a jack 35 for the shoe, a series of formers having clamping edges adapted to be engaged with the edge of the shoe without projecting over the sole thereof, said formers each having a flat upper surface adapted to be on the plane 40 of the innersole as a support for the out-turned edge of the upper when the former is thus engaged with the shoe, and means for independently adjusting each of said formers manually toward the work.

16. A lasting machine comprising a jack 45 for the shoe, and a series of formers adapted to be engaged with the edge of the shoe, said formers each having a flat upper surface with a recessed inner edge adapted to be on 50 the plane of the innersole as a support for a welt and the out-turned edge of the upper when the former is thus engaged with the shoe.

17. A lasting machine comprising a jack 55 for the shoe, a series of formers having inner clamping edges, said inner edges providing a continuous recess for the reception of a welt, and means for varying the width of said recess for welts of various widths.

18. A lasting machine comprising a jack 60 for the shoe, a series of formers having inner clamping edges adapted to be moved against the shoe, an adjustable plate secured upon the upper face of each former, the inner edge of said plate being parallel to that

of its former and coacting therewith to form a continuous recess for the reception of a welt, said plate also constituting a flat support over which the shoe upper is adapted to be folded, and means for securing said plate at various positions to accommodate 70 welts of various widths.

19. A lasting machine having, in combination, a base, a table rotatable thereon about a vertical axis, a carriage mounted to slide 75 transversely of the table and supporting a last pin, a second carriage supporting a toe rest and a flexible toe clamp, and adjusting means connected with both carriages for sliding them together from and toward the 80 center of the table.

20. A lasting machine having, in combination, a table, a heel rest carriage, a second carriage supporting a toe rest and a toe clamp, an adjusting screw having right and 85 left threaded engagement with said carriages, and an adjustable connection between said screw and the table by means of which the two carriages and the screw may be adjusted together on the table. 90

21. A lasting machine having, in combination, a flexible toe clamp or former, a heel rest carriage, a heel post mounted in said carriage, a beveled gear confined for turning movement in said carriage and having 95 threaded engagement with the post, a horizontal adjusting shaft and a beveled gear on said shaft meshing with the first mentioned gear for adjusting the heel post relatively to the toe clamp. 100

22. A lasting machine having, in combination, a flexible toe clamp or former, a toe rest, a heel post which comprises a forked support, a last pin pivoted in the support and having a toothed lower end, a lever fulcrumed in the support and having toothed engagement with said last pin, and an adjusting rod threaded in a fixed support and connected with said lever for rocking the last about its pivot. 110

23. A lasting machine having, in combination, a toe rest carriage, a toe rest thereon, a flexible toe clamp or former, a clamp carrier, and a sliding clamp support mounted for adjustment in said carriage toward and 115 from the toe rest.

24. A lasting machine having, in combination, a toe rest carriage, a toe rest thereon, a flexible toe clamp or former, a clamp carrier, a sliding clamp support mounted for 120 adjustment in said carriage toward and from the toe rest, means for locking said support against movement away from the rest, and additional means adapted for thereafter pressing the clamp toward the rest. 125

25. A lasting machine having, in combination, shoe supporting means and a flexible end clamp or former, arms connected together and having connection with the clamp near the closed end portion of the 130

5 clamp, links connecting the outer ends of the clamp with said arms, and means for actuating said arms to apply inward and backward pressure to the clamp for tightening it around the end of the shoe.

26. A lasting machine having, in combination, shoe supporting means and a flexible end clamp or former, arms connected together and forming an end abutment for the 10 closed end portion of the clamp, links connecting said arms with the free end portions of the clamp, and a hand wheel and operating rod connected with the ends of said arms beyond the links for drawing the arm ends 15 together and thereby causing the links to exert on the clamp ends an inward and rearward pressure.

27. A lasting machine having, in combination, last supporting means including a 20 toe rest, a toe clamp or former, a support therefor between which and the toe rest there is provision for relative adjustment, a former carrier connected with said support by a pivot extending transversely of 25 the shoe, means for adjusting said carrier about said pivot, and means for operating the carrier to cause the end portions of the former to clamp the upper against the sides of the toe portion of the last.

30. 28. A lasting machine having, in combination, a toe rest, a toe former, a support for the former, a forked rod having adjustable connection with the toe rest and embracing the toe former support, and a cam lever carried 35 by said rod in position to engage the support and through said support to force the former against the end face of the last.

29. A lasting machine having, in combination, last supporting means; an end embracing band, a carriage movable to position the band against the end of the shoe; means 40 acting directly through the closed end portion of the band, and also through its free end portions, for giving to the band an additional movement lengthwise toward the 45 shoe.

30. A lasting machine having, in combination, last supporting means, an end embracing band, a carriage movable to position the band against the end of the shoe, 50 means for holding said carriage in adjusted position, and means acting against the closed end portion of the band for giving thereto additional movement against the 55 shoe.

31. A lasting machine having, in combination, means for supporting a shoe; a toe 60 clamp or former adapted to embrace the toe portion of the shoe; means for adjusting said former to position its upper edge face flush with the sole face of the last; and ball and side formers arranged to present, in combination with said toe former, a continuous surface over the top face of which 65 the vamp may be folded outwardly.

32. A lasting machine having, in combination, means for supporting a shoe; a toe clamp or former adapted to embrace the toe portion of the shoe; means for adjusting said former to position its upper edge face 70 flush with the sole face of the last; and ball and side formers arranged to present, in combination with said toe former, a continuous surface over the top face of which the vamp may be folded outwardly; said ball and shank formers being recessed and arranged with their recessed surfaces flush with the top of the toe former and presenting at the outer edge of said recesses a welt positioning wall.

33. A lasting machine having, in combination, a former 73 adapted to engage the side of the shoe and clamp the upper against the side face of the last, a stem 75 to which the former is adjustably connected for positioning movement about an axis extending transversely of the shoe, and a support 77 in which the stem is adjustable endwise and 75 rotatively for further positioning the former.

34. A lasting machine having, in combination, a former adapted to clamp the upper against the side face of the last, a rocking arm in which said former is carried for movement toward and from the last, an 90 actuator and yielding connections between it and the former through which the former is pressed against the last, and means for locking the actuator with the former held under yielding pressure.

35. A lasting machine having, in combination, a former to clamp the upper against a side face of the last, a carrier therefor, an actuator by which the carrier is moved to force the former against the last, means to 105 maintain the actuator in adjusted position, a lost motion connection between the actuator and the carrier including abutting faces through which movement is unyieldingly transmitted, and a spring arranged to be 110 compressed during said lost motion and to exert yielding pressure against the former while the actuator is locked.

36. A stitchdown shoe lasting machine having, in combination, means for supporting a last, and formers arranged to press the upper against the sides of the last adjacent to the edge of the shoe bottom and shaped to hold an upper retainer over which and the formers the upper may be pulled up 115 and laid out upon the top face of said retainer and former, said upper retainer being shaped to fit in the former and adapted to adhere to the upper for holding the latter in up-pulled and outlaid position and to coöperate with the former in shaping the upper at the edge of the shoe bottom.

37. A stitchdown shoe lasting machine having, in combination, a shoe support and a former adapted to clamp the upper 120 125 130

against the sides of the last and shaped to receive an upper retainer over which and the top face of the former the flange of the upper is outturned, said upper retainer being shaped to fit into the former and adapted to adhere to the upper and to coöperate with the former in shaping the crease or angle that is between the side face of the shoe and the outturned flange of the upper.

10 38. A stitchdown shoe lasting machine comprising a support for the shoe, rigid formers adapted to be brought into contact with the side edges of the shoe along the line of the edge of the insole, each of said formers having an outwardly extending flat surface, means for causing each former to exert an independent yielding pressure against the shoe, and means on said formers for shaping a welt edgewise into conformity 20 with the edge contour of the side of the last.

15 39. A stitchdown shoe lasting machine having, in combination, a shoe support, formers adapted to extend along the sides of the shoe and having their inner edges recessed for the reception of a welt strip, and means for causing said formers to clamp the upper yieldingly against the last.

25 40. A stitchdown shoe lasting machine having, in combination, a shoe support and

shoe edge embracing means over which the 30 margin of the upper is to be outturned and shaped to produce the sole attaching flange, said embracing means having a non-rigid surface along the line on which the margin is outturned.

35 41. A stitchdown shoe lasting machine having, in combination, a shoe support, and means for presenting and holding a welt relatively to the shoe support in such manner that the upper can be turned outwardly 40 over an edge of the welt whereby the welt is located by such outturning in the angle formed between the body of the shoe and the sole attaching flange.

42. A stitchdown shoe lasting machine 45 having, in combination, a shoe support, and means arranged relatively to said support for confining a welt against outward and downward displacement from position to have the upper turned over it and com- 50 pressed between it and the outsole.

In testimony whereof I have affixed my signature, in presence of two witnesses.

WILLIAM S. HAMM.

Corrections in Letters Patent No. 1,106,377.

It is hereby certified that in Letters Patent No. 1,106,377, granted August 11, 1914, upon the application of William S. Hamm, of Boston, Massachusetts, for an improvement in "Lasting-Machines," errors appear in the printed specification requiring correction as follows: Page 4, line 28, for the word "upper" read *welt*; same page, line 31, for the word "welt" read *upper*; same page, line 40, strike out the reference-letters and words "c and the edges of it cover the edge b'" and insert the reference-letter and words *e is then laid upon the shoe, (See Fig.)*; page 5, line 23, for the words "brought independently" read *independently brought*; and that the said Letters Patent should be read with these corrections therein that the same may conform to the record of the case in the Patent Office.

Signed and sealed this 6th day of October, A. D., 1914.

[SEAL.]

R. F. WHITEHEAD,

Acting Commissioner of Patents.
